UNITED STATES PATENT OFFICE.

JAMES E. LOSHBOUGH, OF ELKHART, INDIANA.

TRIPPING MECHANISM FOR PUNCH PRESSES.

Application filed December 4, 1925. Serial No. 73,268.

This invention relates to improvements in power presses and particularly it refers to that mechanism in pressing, punching machines and the like by means of which the operator arbitrarily may either effect the stoppage of the press automatically after each cycle of operations, or may effect continuous operation.

It is, therefore, an object of the invention to incorporate with the drive of a power press a clutch and operator controlled means for locking the clutch in inoperative position, or for holding it in a position in which the operation is repeated, and to combine with it a non-repeat mechanism, by means of which the clutch is moved into inoperative position after each cycle of operations.

It is an object, furthermore, of the invention to effect the release movement of a clutch part by means of a projection on an operative organ of the machine, said projection passing a fixed point once in each operation, and influencing the movement of a control element through which a locking member is positively moved to a position in which it locks the clutch part against entry to operative position.

With these and numerous other objects in view, an embodiment of the invention is described in the accompanying specification in which reference is made to the drawings.

In the drawings:

Fig. 1 is a side elevation of a press to which the clutch control mechanism is applied; Fig. 2 is a front elevation, and partly sectional view on a larger scale, of the clutch part and control elements; Fig. 3 is a side elevation of part of the control mechanism similar to that illustrated in Fig. 1, but showing the parts in a different position, and on a larger scale;

Fig. 4 is a sectional view and part elevation of the clutch part and its carrier;

Fig. 5 is partly a front elevation and partly a sectional view of the parts illustrated in Fig. 4;

Fig. 6 is a bottom plan view partly in section of the locking member and clutch part;

Fig. 7 is a detail sectional view of a link connection between a manually operated part and the automatic non-repeat mechanism;

Fig. 8 is a sectional view through the parts illustrated in Fig. 7, seen from the opposite side, and

Fig. 9 is a detail sectional view on line 55 9-9 of Fig. 8.

The machine to be controlled by the appliance forming the subject matter of the present application is shown as a power press, having the pedestal 1, a frame 2 oscillatably mounted thereon, a press bed 3, and an overhanging part 4 on which the punching or pressing mechanisms proper of the machine, not illustrated in the drawing, may be suitably guided. The arrangement of these parts does not form the present invention, and for this reason these parts are not described in detail in the specification.

The drive of the machine may be derived from some suitable source, not illustrated, and may be communicated to the machine by means of the shaft 5 which is supported in bearings one of which is indicated at 6 in Fig. 2. This shaft also loosely supports a combined flywheel and belt pulley 7 over which the driving belt, not shown, is trained.

While this flywheel or belt pulley 7 is loosely mounted on the shaft, the latter supports fixed thereto a ring 8 acting as a carrier for a clutch part 10 by which a driving relation 75 80 between the shaft 5 and the belt pulley 7 may be established.

The pulley 7 for this purpose is provided with sockets 9 one of which only is indicated in Fig. 2 in that face of its hub which is next to the ring 8. The ring 8 is shown as comprising a portion of a larger and a portion of a small diameter. A preferably rectangular opening 11 extends axially through the portion of larger diameter and is continued as 90 a groove 12 in the portion of smaller diameter. The opening 11 and groove 12 have a lining or guide bushing 13, Fig. 5, to facilitate sliding movement of the clutch part 10.

This part is constructed as a pin of a cross-section corresponding to the area confined by the lining 13. A transverse groove 14 extends thru the pin intermediate its ends, advisably at such distance from the front end of the pin that in retracted position, Fig. 4, of this clutch pin one wall of the groove 14 is substantially flush with the rear face of the portion of larger diameter of the ring 8. The bushing 13 is secured in place within the ring 8 by means of the screw 15.

The clutch part also has an axial recess 19 adapted to receive the means for normally advancing the part to operative position,

these means being illustrated in Fig. 4 as a spring 16 seated within the socket 19 and resting on the bottom of the same, while the opposite end of the spring surrounds a pin 17 forming an angular extension of another pin 18 which is driven tightly into the smaller portion of the ring 8.

When the clutch part 10 is advanced from the position shown in Fig. 4 into a socket 9 of the belt pulley 7, as shown in Fig. 2, rotary movement will be communicated to the shaft 5, while upon withdrawal of the clutch part 10 into the position shown in Fig. 4 the belt pulley 7 will rotate loosely on the shaft, while the shaft will remain at rest. It is, furthermore, obvious that normally the spring 16 acting on the clutch part 10 will cause the same to be advanced to clutch position. The invention, therefore, comprises means under the control of the operator of the machine for selectively, either locking the clutch part 10 against movement to operative position, Fig. 4, or for releasing this lock, in which latter case the clutch part 10 will automatically be advanced to operative position, Fig. 2.

The locking member 20 is formed as a lever pivoted on the bolt 21 in a fixed part of the machine frame 2. The pivotal support of the lever 20 is so close to one end of the same that this locking lever will under its own weight assume the position indicated in Fig. 3, in which it is withdrawn from locking position, so that the clutch part 10 will be advanced to clutch position. In Figs. 1 and 4, however, the locking member 20 is shown in locking position, preventing thereby the movement of the clutch part 10. The locking member 20 is so disposed with respect to the clutch part 10 that it is adapted to enter the groove 14, even if this clutch part is fully advanced, Fig. 2, and the upper margin of the locking member 20 is for this purpose provided with a beveled cam edge 22 facilitating the entry of this marginal part to operative position, and effecting by this entry into the groove 14 of the clutch part a positive return movement of said part to inoperative position, Fig. 4, against the action of the spring 16.

To prevent upon withdrawal of the locking member 20 of the clutch element 10 from being advanced too far by the spring and being pushed out of the squared opening 11, a safety stop 23 is indicated in Fig. 5, said stop comprising a pin disposed at a right angle to the direction of movement of the clutch part 10 and adapted to engage the clutch pin after the same has been advanced a predetermined extent. According to Fig. 2 this maximum advance of the clutch part 10 brings the front face of the pin a slight distance from the bottom of the socket 9 in the driving pulley 7.

65 The locking member 20 drops under its own

weight automatically to inoperative or lock release position, Fig. 3. Means under control of the operator are provided for effecting the return of this locking member 20 to operative or lock position, and for holding it there.

A treadle lever 24 is pivoted at 25 in the pedestal and a rod 26 is flexibly connected to the treadle lever 25 intermediate its ends; it carries at its top a connector 27 by means of which this rod 26 is movably associated with a bar 28. This bar is guided in two flanges, the flange 29 part of a bracket 30 fixed to the frame 2, and the flange 31 being adjustable on the bracket 30 in a vertical slot, Fig. 1. The bar 28 forming an offset extension of the link 26 is surrounded in its lower portion by a spring 32 resting below on flange 29, while the top of the spring engages a collar 33 adjustably fixed on the rod 28. The spring 32, therefore, has a tendency to return the bar 28 and link 26 and treadle lever 24 to the position shown in Fig. 1 when the treadle is released, the spring urging the collar 33 against the flange 31.

Another spring 34 surrounds the upper portion of bar 28 between flange 31 and a washer 35 loosely mounted on this bar. The second spring 34, therefore, normally has a tendency to force the washer 35 upward, regardless of the depression of the treadle.

The control means for the locking member 20 include in addition to the elements described a bell crank lever 36 mounted pivotally on a bolt 36' fixed in the machine. The arm 38 of this bell crank projects upward and is connected by links 37 with the locking member 20 intermediate the ends of the same, the latter being provided with a transverse bore 39 through which the attachment pin for the links 37 extends. The arm 38, furthermore, has a lateral extension 40 terminating in an upwardly directed lug 41 of such height that the lever 36 assuming the position shown in Fig. 1 will engage by means of the lug 41 the rear portion of the locking member 20 and will assist in forcing said locking member to operative or locking position, Fig. 1.

The other arm 42 of the bell crank 36 is bifurcated at its free end, Fig. 9, the prongs 43 being provided with noses which rest upon the washer 35. A pin 44 is journaled transversely of and in the prongs 43 and is provided between them with a notch 45 of substantial depth and having a flat bottom. A notch 46 in the extension 47 of bar 28 above the washer 35 has oppositely inclined end walls 48, 49 and a slightly slanting flat bottom wall 50, Fig. 8.

Normally the spring 34 forcing the arm 42 upward, Fig. 8, will urge the edge of the flat part of notch 45 of pin 44 against the upper slanting bottom wall 48, whereby the bell crank arm 42 is stopped against further upward movement.

A block 51 is slidably supported on the extension 47 of the rod 28 and is for this purpose equipped with a longitudinal bore 52 of a sufficiently large diameter. It also has a transverse bore in which the pin 44 may rock.

The pin 44 has a reduced extension 53 projecting laterally from a prong 43 of the bell crank arm 42, and fixedly connected with the reduced extension 53 is a lever 54. One arm 10 of this lever terminates in a lug 55 to which a link 56 is movably secured. The opposite arm has on its lower surface a socket 57 in opposition to a lateral socket 58 on a prong 43 of the bell crank lever 36. A spring 59 is seated in both of these sockets, Fig. 7, thereby normally forcing the opposite end of the lever 54 downward, Figs. 1, 7 and 8.

The pivot 21 on which the locking member 20 is mounted also carries a control lever 60 having one end directed towards the clutch carrying ring 8 and being provided adjacent said end with a cam nose 61 for engagement with a release cam 62 which is secured in the circumference of the clutch ring 8 and which at each revolution of the clutch ring therefore once engages the cam nose 61 of the control lever 60 to depress the same about its pivot 21.

The control lever 60 for the locking member 20 is extended beyond this fulcrum 21 and is bifurcated at 63, the prongs of the fork having upward extensions 64. The upper threaded part of link 56 is inserted into this fork, and a sleeve stop 65 is slidably secured on the link to impinge with its lower end on the control lever 60 while upward movement is prevented by the adjustable nut 66 on top of the sleeve. It is obvious, therefore, that upon suitable adjustment of the sleeve stop, the link 56 will be held within the fork 63 of the control lever 60, while upon loosening of the nut 66 and displacement of the stop 65 the link 56 may be readily disconnected.

When in the operation of the press it is desired to establish and maintain the drive of shaft 5, the link 56 may be disconnected, or even the control lever 60 may be removed. The operator, depressing the treadle lever 24 will pull the link 26 and bar 28, to bring the edge of the flat bottom of notch 45 on pin 44 into engagement with the wall 48 of the notch in the extension 47, as shown in Fig. 8. The position of the bell crank 36 is not affected by this operation and the parts 20, 36, 60 remain in the position shown in Fig. 1, holding the locking member 20 in locking position. If however the depression of the treadle is continued, a further downward movement of bar 28 will now also cause the pin 44 to move 60 along with it downward, and this naturally also moves the arm 42 of bell crank 36 down about its pivot 36, removing the holding lug 41 from the rear end of locking member 20, so that the latter drops to release position, aided by the links 37. The parts are shown in

this position in Fig. 8, in which, however, the link 56 is shown in place.

Spring 16 in the ring 8 now forces the clutch pin 10 into a socket 9 in the flywheel 7, as soon as this socket is in opposition to the pin, and the shaft 5 is then positively driven with the flywheel or belt pulley.

In each rotation of the ring 8 the projection 62 on its circumference may enter into engagement with the control lever 60 and may tilt the same. But since the rear bifurcated end 63 of this lever is in this operation not connected with the link 56, this tilting movement will have no influence on the operator controlled parts. The press, therefore, will continue to operate until the operator releases the treadle, so that the pin 44 through the spring enforced upward movement of the rod 28 is forced upward, tilting arm 42 upward and pushing thereby by means of links 37 and arm 41 the locking member 20 positively into locking position, and retaining it in this position until the treadle is again depressed.

Normally, pedal 24 is depressed by the operator, and to gain another revolution of 90 the press crank-shaft, and thereby a movement of the press ram, the pedal 24 is released and again depressed. When the pedal 24 is thus released, as above mentioned, the spring 34 actuates the bell-crank 36 back to the position indicated in Fig. 1 and rods 28 and 47 are elevated thereby, causing pin 44 to engage notch 48. The press is then at a standstill as locking lever, or latch, 20, is raised and the lock bolt or clutch 10 has been retracted thereby. When the pedal 24 is again depressed, as above mentioned, the rods 28 and 47 are drawn downward thereby, the bell-crank lever arm 42, which is connected with the pin 44 by the fork 43, being tilted downward thereby, due to the engagement of the pin 44 with notch 48 in rod extension 47, whereby the arm 40 of said bell-crank lever and the locking lever or latch 20 are lowered, the latter through link 110 37, thereby releasing the lock bolt 10 which again enters the wheel bolt socket. The press crank-shaft then rotates and a single operative movement of the press is effected. The disk 8 is rotated with the shaft 5 and the cam 62 thereupon engages the end of the tripping lever 60 adjacent said disk, tilting said lever, the opposite end 63 of said lever being upwardly tilted thereby, whereby the link 56 tilts the lever 54 upward, thereby disengaging the pin 44 from the notch 48.

Thereupon, the spring 34, which engages beneath the rod flange or disk 35, and upon which disk the fork 43 of bell-crank lever arm 42 is seated, tilts said arm 42 upward, thereby sliding the block 51 upward along the rod 47 and carrying the detent pin 44 to a point above the notch 48 and in slidable engagement with the surface of said rod extension. Thus, with the upward tilting move- 120 125 130

ment of the bell-crank lever arm 42, the link 37 elevates the locking lever or latch 20 and the lock bolt 10 is again retracted thereby; and the point 41 of the bell-crank lever arm 5 40 again engages the base of the lever 20 and aids in maintaining the latter in the elevated position, also limiting the upward swing of the bell-crank lever arm 42. The press is now at a standstill. For convenience, 10 the rocking pin 44 may be designated as a detent element or pin, and when the link 56 is connected with the lever 60, the tripping lever 60, the portion 63 thereof, the link 56 and lever 54 may be designated as tripping 15 mechanism.

When it is desired, however, to automatically interrupt the press after each complete revolution of the shaft 5, the lever 54 fixedly attached to the pin 44 is connected by means 20 of the link 56 to the bifurcated end 63 of the control lever 60, and the sleeve stop 65 is applied to maintain this connection. The inactive position of the press is again as shown in Fig. 1. When now the operator depresses 25 the treadle lever 24 and pulls the rod 28 downward, the pin 44 again will engage wall 48 of the notch in the extension 47, and continued depression of the treadle will again cause release of the locking member 20, as 30 described above. In this instance the downward movement of link 56 also will cause the front end 61 of the control member 60 to move closer to the path of the projecting pin 62.

35 If now, however, upon completion of a cycle of operations, that is, upon one complete revolution of the shaft 5, the lug 62 on the clutch ring 8 strikes the cam surface 61 of the control member 60, it will tilt said 40 control lever downward at its left end, Fig. 1 or 3, thereby pulling the opposite end 63 upward and exerting also an upward pull on the link 56. This upward pull will now cause the lever 54 to turn, compressing the 45 spring 59. Owing to this rocking movement of the lever 54 the pin 44 fixedly connected with it is rocked out of locking engagement with wall 48, and the spring 34 which had been compressed will snap to expanded 50 position forcibly turning the bell crank 36 from the position shown in Fig. 3 to the position of Fig. 1. The links 37 connecting the bell crank 36 with the locking member 20 will again push said locking member 55 back into the transverse groove 14 of the clutch pin to force the latter back against the action of spring 16. The holding lug 41 of the bell crank lever 36 again will act on the rear end of the locking member 20 to 60 prevent the drop of the same to inoperative 65 position.

This return tilting movement of the bell crank 36 is effected in spite of the fact that the operator holds the treadle and bar 28 depressed. If it is then desired to start the press

again and to have it execute a single stroke followed by a rest period, the operator again first releases the treadle and then again depresses it to bring the parts once more into the position shown in Fig. 3.

I claim:

1. In a power press, the combination with a driven shaft, a driving wheel, a spring pressed locking bolt adapted for alternate engagement and disengagement with said driving wheel, and a tiltable locking lever adapted to alternately retract and release said locking bolt, of a cam on said driven shaft, a tripping lever tiltably mounted intermediate its extremities and adapted to be tilted by said shaft cam, a bell-crank lever, actuating linkage connecting said bell-crank lever with said locking lever, spring means normally urging said bell-crank lever for actuating said locking lever to retract said locking bolt, a spring pressed foot-pedal, a rod connected with said pedal, detent means carried by one arm of said bell-crank lever and engageable with said foot-pedal rod, and disengaging means operatively connecting said detent means with said tripping lever for disengaging said detent means from said rod when said tripping lever is tilted by said cam.

2. In a power press, the combination with a driven shaft, a driving wheel, a spring pressed locking bolt adapted for alternate engagement and disengagement with said driving wheel, and a tiltable locking lever adapted to alternately retract and release said locking bolt, of a cam on said driven shaft, a tripping lever tiltably mounted intermediate its extremities and adapted to be tilted by said shaft cam, a bell-crank lever, actuating linkage connecting said bell-crank lever with said locking lever, spring means effecting pressure upon one arm of the bell-crank lever for normally urging the latter for locking lever actuation to retract said locking bolt, a spring pressed foot-pedal, a rod connected with said pedal, detent means carried by one arm of said bell-crank lever and engageable with a recess in said pedal rod, said detent means including a spring pressed rotary element journaled in said bell-crank lever arm, and disengageable linkage operatively connecting said detent means with said tripping lever for disengaging said detent means from said rod when said tripping lever is tilted by said cam.

3. In a power press, the combination with a driven shaft, a driving wheel, a spring pressed locking bolt adapted for alternate engagement and disengagement with said driving wheel, and a tiltable locking lever adapted to alternately retract and release said locking bolt, of a cam on said driven shaft, a tripping lever tiltably mounted intermediate its extremities and adapted to be tilted by said shaft cam, a bell-crank lever, a link connecting said bell-crank lever with said lock-

- ing lever for actuating the latter, a lateral projection from one of the bell-crank lever arms adapted to engage the locking lever when the latter engages said locking bolt, 5 spring means normally urging said bell-crank lever for actuating said locking lever to retract said locking bolt, a spring pressed foot-pedal, a rod connected with said pedal, 10 detent means carried by one arm of said bell-crank lever and adapted to engage said pedal rod for normally restraining the action of said spring means on said bell-crank lever, and disengageable disengaging means operatively connecting said detent means with said 15 tripping lever for disengaging said detent means from said rod when said tripping lever is tilted by said cam.
4. In a power press, the combination with a driven shaft, a driving wheel, a spring 20 pressed locking bolt adapted for alternate engagement and disengagement with said driving wheel, and a tilttable locking lever adapted to alternately retract and release said locking bolt, of a cam on said driven shaft, 25 a tripping lever tiltably mounted intermediate its extremities and adapted to be tilted by said shaft cam, a bell-crank lever provided with a forked arm, actuating linkage connecting one arm of said bell-crank lever with said locking lever for actuating the latter when the former is tilted, spring 30 means for effecting resilient pressure upon said forked bell-crank lever arm for normally urging the latter to effect locking lever actuation to retract said locking bolt, a spring 35 pressed foot-pedal, a rod connected with said pedal and movable therewith, detent means carried by the forked arm of said bell-crank lever and engageable with a recess in said pedal rod, said 40 detent means including a detent pin rotatably mounted in said bell-crank lever arm fork, a block in which said pedal rod is slidably mounted, and a spring pressed lever connected with one end of said rotary detent pin, 45 and disengageable disengaging means operatively connecting said detent means spring 50 pressed lever with said tripping lever for disengaging said detent pin from said rod recess when said tripping lever is tilted by said shaft cam.
5. In a power press, the combination with a driven shaft, a driving wheel, a spring 55 pressed locking bolt adapted for alternate engagement and disengagement with said driving wheel, and a tilttable locking lever adapted to alternately retract and release said locking bolt, of a cam on said driven shaft, a tripping lever tiltably mounted intermediate its extremities and adapted to be tilted by said shaft cam, a bell-crank lever 60 provided with a forked arm, actuating linkage connecting one arm of said bell-crank lever with said locking lever for actuating the latter when the former is tilted, spring 65 means for effecting resilient pressure upon said forked bell-crank lever arm for normally urging the latter to effect locking lever actuation to retract said locking bolt, a spring 70 pressed foot-pedal, a rod connected with said pedal and movable therewith, detent means 75 carried by the forked arm of said bell-crank lever and engageable with a recess in said pedal rod, said detent means including a block arranged in the fork of said bell-crank lever forked arm, a detent pin rotatably mounted in said block and bell-crank lever arm fork and in communication with a bore in said block in which said pedal rod is 80 slideable, and a spring pressed detent pin actuating lever mounted upon one end of said pin, and a disengageable disengaging link operatively connecting said detent means spring 85 pressed lever with said tripping lever for disengaging said detent pin from said rod recess when said tripping lever is tilted by said shaft cam.

In witness whereof I have hereunto affixed my signature this 28th day of November, 1925.

JAMES E. LOSHBOUGH.
